UNITED STATES PATENT OFFICE

2,654,377

DISHWASHING MACHINE

Henry C. Sway, Bridgeport, Conn., assignor to
General Electric Company, a corporation of
New York.

Application February 9, 1949; Serial No. 75,466

7 Claims. (Cl. 134—93)

1

This invention relates to improvements in dishwashing machines, and has for a principal object the simplification of construction and improvement of operation of dishwashers of the domestic type.

It will be apparent as the description of the invention progresses that features of the invention may be used to advantage in any dish-washer of the impeller or dasher type, but the mechanical simplicity and ease of control are perhaps best suited to low-cost machines in which the various stages of washing and rinsing are manually controlled.

Among the objects of the invention are the provision of novel means for insuring that the dishwasher tub receives the correct quantity of water for dishwashing and rinsing; a simplified but effective means for introducing a measured quantity of detergent material into the tub; a simplified, two-position control for the filling, washing, rinsing and draining operations; an improved pump cover and an improved water flow limiter at the impeller and the drain pump to substantially eliminate the noisy surging and pulsing of water during washing and draining; and an improved drain and check valve.

These and other features and advantages will be apparent from the following detailed description of a typical embodiment of the invention, taken in conjunction with the accompanying drawings in which:

Fig. 1 is a perspective showing a typical portable dish washer embodying the present invention, as connected to the faucet of a kitchen sink; Fig. 2 is a vertical sectional elevation of a presently preferred embodiment; Fig. 3 is an enlarged sectional detail of the cover and drain valve, illustrating the operation of the control for respectively filling the cover and permitting the contents thereof to flow through the detergent cup into the tub; Fig. 4 is a top plan view of the handle and control panel with a portion of the top cover structure being broken away to show the relative position of the fill valve and its relation to the control rod; Fig. 5 is a bottom plan detail showing a suitable detent means for holding the control rod in either of its two operative positions; Fig. 6 is a rear elevational view of a suitable cover hinge and drain valve assembly; Fig. 7 is a side elevational view taken in section on lines 7—7 of Fig. 6 to show the operation of a detent means for retaining the cover in raised position; Fig. 8 shows the status of the discharge valve control rod with the cover in raised position; Fig.

2

9 is a top plan view of a portion of a cover with a piece of the upper cover wall and the upper hinge structure broken away to show a suitable manner of introducing water into the cover chamber; and Fig. 10 is a plan view of a preferred form of pump chamber cover.

Referring to the drawings, Fig. 1 shows a dish-washer 20 of the portable type and arranged by means of the sink faucet fitting 21 to receive water through a flexible hose 23 and to discharge water to the sink through the hose 24. A suitable construction of the faucet fitting is shown in Fig. 2 wherein it appears that the body thereof is divided by means of a web 25 into mutually independent inflow and outflow chambers. A conventional electric cord 26 when plugged into the usual outlet provides power for the motor 27. A switch (not shown) may be included in the motor circuit, but it is possible to dispense with a control switch, so as to have the motor start solely as the result of inserting the plug into the outlet.

A presently preferred construction includes a tub 28 which is suitably carried on a base 30, the lower portion of the tub telescoping into the base as shown. The conical bottom of the tub forms a dishwasher impeller chamber which provides a suitable water level for impeller operation with but one gallon of water in the tub. The motor 27 may be supported or steadied by beams 31 or equivalent, which are suitably anchored at the circular toe plate 32. Casters 33 may be provided, if desired. A suitable plurality of brackets 34 extending inwardly from the tub 28 carry a skeletal wire frame 35 having means for supporting glasses, cups, and the smaller size dishes, at various locations about its periphery. The glasses are most advantageously placed bottoms up on the upwardly sloping central portion of the frame. A suitable mesh basket 36 is preferably placed near the wall of the tub to accommodate silverware and the like. A second wire frame 37 rests on the base of the tub; said frame has a plurality of supports 38 against which dishes may be stacked. It will be understood that the frames 35 and 37 are provided with a relatively large plurality of dish supporting structures; they have been eliminated from the drawings for simplification of disclosure. A wire screen 40 of suitable mesh—for example one half inch—is secured to the underside of frame 37 and extends completely across the bottom of the tub above the impeller chamber so as to prevent silverware or other small articles which might have been

dropped during the loading of the machine, from fouling the impeller.

In a dishwasher of the impeller type, it is preferable to arrange the motor 27 so that its shaft 41 will extend vertically upwardly concentric with the tub 28. A sleeve or bearing 42 for the motor shaft may be integral with and extend upwardly from the lower wall 43 of the pump chamber 44. It will be understood that suitable seals (not shown) protect against contamination of the wash water with lubricant and prevent water from passing into the motor. Advantageously, the pump chamber is formed as part of the motor housing and affords means of securing the housing to the bottom of the tub, as by screws 45 or equivalent. It will be understood that gaskets and other leakage-preventing means are provided to seal the aperture at the bottom of the tub. Sleeve 42 extends upwardly to a point substantially above the static water level, WL, and at its upper end is provided with suitable water sealing means (not shown). Fixed to the upper end of the shaft 41 is a tubular hub structure 46 which extends about the bearing 42 in concentricity therewith. Suitably secured to hub 46—advantageously integral therewith—is a pump impeller 47 which, as later explained, pumps water outwardly through the discharge conduit 48 to the discharge control valve 50 and thence to the drain connection 24. Also affixed to the motor shaft and carried by the upper end of the pump hub 46 is the hub 51 of the impeller 52. The impeller and its hub may be molded from rubber compounds or plastic materials which are satisfactorily abrasion resistant. The impeller blades have a sharp angle of attack as is apparent in Fig. 2 and the motor and impeller are capable of substantial water movement—for example, at the rate of 50 gallons per minute.

A present embodiment of a dishwasher embodying the present invention operates most satisfactorily on one gallon of water, said quantity filling the lower portion of the tub to a point wherein the impeller 52 is approximately one-half submerged. A feature of the invention resides in the use of a chamber associated with the cover to measure the water with substantial accuracy. As appears to best advantage in Fig. 2 the water chamber may be formed by the cover itself, by making the cover of hollow construction, in which an upper member 53 which is shaped to form a convex top wall and cylindrical side wall cooperates with a contoured bottom wall 54 suitably secured to the member 53. Preferably the point of securing is at an outwardly extending peripheral lip 55 which forms an anchor for gasket 56 which seats on a ledge 57 of the tub when the cover is closed. The central portion of the bottom wall 54 is domed as at 58 and at its center is provided with an opening 59. Said opening is partly closed by a baffle 60 which is supported by a bracket 61 affixed to the cover member 53, said shield having any desired number of side wall openings 60a. The inflow hose 23 seats telescopically about a rigid inlet pipe 62 which enters a side wall of an upper hinge cover plate 63, and then extends into the cover chamber, terminating at any suitable location therein. In the illustrated embodiment the pipe 62 is illustrated as being in contact with the underside of the cover member 53, thereby being suitably above the maximum cover water level, C. W. L., to provide an air gap sufficient to pre-

vent back siphonage from the cover to the fill line. The end of the pipe may be baffled or the pipe provided with bridge means or the like for supporting it within the cover, as a matter of choice. As best appears in Fig. 3 an opening in the bottom cover member 54 is provided with a plate-like structure 64 which defines a valve seat 65 extending upwardly into the cover. Said valve seat cooperates with a valve disk 66 to permit the cover chamber to be filled, or drained into the tub according to the operating position of the disk. An open-topped detergent cup or container 67 fits snugly against the underside of plate 64, and forms a conduit through which water flows from the cover into the tub. Suitable side wall channels of container 67 (not shown) engage with side tracks 68 to removably support the container 67 on the plate 64. Preferably, the cup is of molded plastic or like lightweight material.

20 The filling and draining of the cover chamber is controlled by a sliding valve operator 70 having an end portion which extends upwardly through a slot in the cover handle 71, to terminate in a suitable knob 72. A bracket 73 provides a supporting saddle 74 for the rod 70 and also a detent plate 75 for cooperation with the roller-provided detent member 76 affixed to the vertical portion of rod 70. Such construction is detailed in Fig. 5. As is apparent from Fig. 3 the detent rollers will climb over the shoulders formed in detent plate 75 during movement of the valve rod to the left or right and seat in the adjacent valley to retain the valve rod in one or the other position. It is understood, of course, that the detent member 76 is springable so as to permit the rollers to ride over the shoulders. Valve disk 66 is advantageously supported on an arm 77 having an apertured head structure through which the mushroom end 78 of the valve disk structure extends. The valve disk structure has a suitable degree of adjustment relative to the arm 77 to insure secure seating on seat 66. Arm 77 is biased into rotation in valve seating direction by such means as a leaf spring 80 suitably secured as suggested in Fig. 3. The leaf spring forms the double function of biasing the valve as aforesaid and supporting it in proper position relative to the valve seat. Arm 77 is forked at its upper end to slidably receive the rod 70, said rod having a short cross pin 81 which is immediately to the right of the arm 77 as viewed in Fig. 3. It is obvious that when the control knob 72 is pushed leftwardly to the dotted position of Fig. 3, the pin 81 will enforce a counterclockwise rotation of the arm 77 to unseat the valve disk 67 and thereupon permit the water to drain into the tub. It will be noted that the cover is vented through one or more ports 82 so that drainage will be free and unimpaired. The vent ports may be covered by suitable rearward extension 83 of the handle 71. As appears best in Fig. 1 the extension 83 provides a suitable plurality of relatively narrow air inflow passages.

65 Movement of the valve rod 70 also controls the operative position of the outflow valve 50. The outflow valve is of angular pattern having a cylindrical body 84, an inflow tube 85 concentric therewith and an outflow tube 86 extending substantially at right angles thereto. At the junction of the inflow and outflow tube the valve body is formed with a shoulder 87 providing a valve seat, as shown to best advantage in Fig. 6. The valve disk assembly includes a resilient disk 88, an elongate weighted stem 90 and a guide washer

which is interposed between the disk 88 and an enlarged head end of the stem 90. Said valve disk assembly is free to move within the valve body axially with the valve disk. Canting or jamming of the disk within the valve body is precluded by the cooperation of the guide washer 91 with the inner side wall of the body, and the pendulum effect of the weighted stem 90. A valve stem 92 is supported for movement axially of the valve body by means of a cap 93 and a flexible bellows 94 which has a thickened wall engaging with the headed end 95 of the valve stem. An opposite end wall 96 is clamped between the cap 93 and the upper shoulder of the valve body to provide a sealing gasket. Within the chamber afforded by the cap and the flexible bellows there is disposed a coil spring 99 which tends to urge the stem 92 downwardly. The upper end of the valve stem is arranged to receive a chain 98 which passes over a suitable roller 99 and provided within the hinge construction and affixes to the end of the rod 70 which, as shown in Fig. 3 extends through a suitable fitting 100 provided in the rear wall of the cover member 53. When the control handle 72 is in its Fig. 3 position the valve disk 88 is seated but the valve stem 92 is raised above the disk assembly of the outflow valve 50. As shown in Fig. 4, this position of the control knob is "fill-drain." When the handle 72 is moved rearwardly it operates to lift the valve disk 66 and to permit the spring 99 to drive the valve stem 92 downwardly so that it engages with the head of the valve disk seat 90 to seat the valve disk firmly on the seat 87. This, as shown in Fig. 4, is at "wash-rinse" control position.

The cover may be counterweighted and suitably spring biased so as to remain in its open or closed positions. Fig. 7 illustrates one form of spring means, namely, a leaf spring 103 suitably anchored in the rearmost hinge structure and having upper and lower detent pockets 104. Arm 105 on the upper cover hinge may have a roller 106 for cooperation with the detent pockets. The lowermost detent pocket is below the pivot point 107 of the cover and hence the reaction of spring 103 tends to urge the cover into closed position. Correspondingly the relative position of the upper detent and the pivot 107 will support the cover in raised position. It will be understood that the cover spring is of relatively conventional construction to which no claim of invention is made and that coil springs or other equivalent means may be used. The weight of the cover and its accessories influences the choice of counterweighting means.

It will be assumed now that dishes have been stacked on their various racks, the detergent cup has been removed, filled to index line DL and returned, and that the cover and control are in the Fig. 3 position. The motor is started, either by simply plugging in the cord, or additionally closing a motor switch (not shown). The user then turns on the water to fill the cover chamber through the flexible hose 23 and the cover conduit 62. After a suitable interval the cover chamber will be filled to its overflow point and the water will enter the tub through overflow ports 60a, and find its way into the pump casing through ports in pump cover 102, as presently described. It is noted that valve 66 is closed and that outflow valve rod 92 has freed the disk so that the outflow from the pump will pass through the valve 50. The user will be apprised of the fact that the cover chamber is at its overflow

point—representing the proper amount of water for satisfactory operation—when a discharge into the sink is observed. It may be that the temperature of water in the cover is then satisfactory, in which event the faucet may be turned off, or the user may continue drawing the water until a satisfactory water temperature is observed. It will be understood that water will continue to flow into the sink through the discharge port of the faucet fitting so long as there is overflow from the cover chamber; this does not represent actual wastage of water for the reason that impeller 52 is operating and therefore will whirl the water within the tub, giving the dishes a preliminary rinse and warming them. The bottom wall shape of the cover, and the baffle 60, deflect the water throughout the tub, improving the preliminary warming and rinsing of the dishes. When the sink faucet is turned off, water will no longer overflow into the tub and very shortly, water flow into the sink will stop. At this stage—and regardless of how long water had been flowing into the cover chamber—the dishwasher will contain approximately one gallon of water in the cover, and only a small amount in the pump casing. The control is then pushed rearwardly to the "wash-rinse" position which will securely close the outflow valve 50 and open cover drain valve 66. Water will then pour from the cover chamber into and through the detergent cup 67 carrying the detergent with it as the water flows into tub 28. As previously stated the static tub water line is at WL; but the rapidly rotating impeller almost immediately throws the water violently upwardly into contact with the articles within the tub. The dishes themselves tend to distribute the water column but it is preferred to place above the impeller a diverter 108, which may advantageously be a ring-like structure having a plurality of angularly arranged vanes 110. In addition it will be noted that the concave cap 60 and the concavity provided by the dome 58 will of themselves divert water striking the cover plate 54 and distribute it through the upper part of the tub. The concentric ridges 111, 112 serve also as baffles or shoulders which direct and distribute water through the tub. Shoulder 112 is particularly effective to insure that the outer circle of utensils placed within the rack 35 are adequately washed, as are the items of silverware placed within the basket 36. The larger plates, pots, etc., which are on the rack 37 are either directly in the path of impeller discharge or receive water as it is whirled about the interior of the tub.

In previous dishwasher constructions of which I am aware an undesirable surging and pulsing may be experienced when the dish load is light. It will be recalled that the impeller has a high water pumping capacity—of the order of 50 gallons per minute—and that there is but a gallon of water within the tub. The water content of the tub is therefore thrown upwardly by the impeller almost at once and returns cyclically to the impeller. In other words, the motor may be subjected to successive high load peaks and intermediate light load valleys. To regulate flow of water to the impeller, and thus to minimize the effect of this cyclic condition, I use a metering ring or wall 114 which is supported by a suitable wire standard 115. The ring or wall extends to, or slightly above, the static water level of the tub. As is shown in Fig. 2 the bottom of the ring is sufficiently above the adjacent bottom wall of the tub to provide a relatively low circumferential

orifice 116 through which the water flows to the impeller. The ring therefore meters water flowing to the impeller, and prevents any substantial amount reaching the impeller above the base thereof. The metering ring effectively reduces the surging which occurs if the water is allowed to circulate freely into the impeller. It will be noted that the ring fits relatively closely about the impeller, at the low point of the bottom of the tub. Thus, after the quantity of water within the ring has been thrown upwardly by the impeller, water flows to the impeller substantially only through the orifice 116. A metered flow of water to the base of the impeller is thereby enforced. The metering ring effectively reduces the critical effect of the quantity of water within the tub. It has been demonstrated that the water quantity may be doubled—increased to two gallons—without overloading the motor.

After the desired washing period the tub is drained by returning the control handle to the "fill-drain" position. The movement of the control rod 70 lifts the valve stem 92 so that the valve disk assembly of the discharge valve 50 is free to lift. It should be understood that all during the washing operation the pump impeller 47 has been rotating inasmuch as it is fixed to the motor drive shaft 41 in common with the impeller hub 51. However, the outlet valve 50 has been held closed by means of the spring 92 and the pump impeller has been rotating idly within the pump chamber; but as soon as the valve stem 92 is raised the pump pressure lifts the valve disk and permits water to flow outwardly through the connection 24 to the discharge port of the faucet fitting. To improve the flow of water into the pump casing, I form the pump cover 102, see Fig. 10, with a central cavity or sump 117 at the center of which is an upwardly extending circular wall 118. Extending tangentially from said wall to the periphery of the cover are vanes 120 and 121, said vanes being approximately the height of the wall 118. In the cover portion defined by the two vanes 120, 121 the pump cover is slotted to provide an arcuate inlet port 122 at the base of the circular wall 118. In the space between vane 121 and a third tangentially extending vane 123 there is no bottom wall opening because said space is adjacent to the discharge or high pressure area of the pump housing. Accordingly, vane 123 terminates short of the ring 118 to provide a flow passage 124 into a cover area defined by the vanes 123 and 120, in which area there is another slot, 125, communicating with the pump chamber. It will be apparent then that the slots 122 and 125 are in the low pressure area of the pump chamber farthest removed from the discharge port. The slot size is such that water will drain rapidly from the tub, but objects which might damage the pump are prevented from entering.

Centrifugal pumps previously used with dish-washing machines and the like have had an inlet opening or openings extending about the full hub circle. In such constructions, noisy splashing and expulsion of water occur through the opening every time a pump blade passes the cutoff point at the outlet. In dishwashers, this undesirable characteristic is most apparent when the pump is operating at the end of the drain cycle. It should also be considered that in dishwashers, this splashing and noise could be of considerable magnitude, for in adapting a centrifugal pump to a desired tub construction it is impossible to have the inlet passage at the very cen-

ter of the pump cover as in the conventional centrifugal pump design. My pump cover construction as shown herein substantially eliminates the splashing and expulsion of water by blanking off the pump cover over the high pressure area of the pump, as explained above. The present pump cover also provides an improved inflow condition at the pump inlet; the tangential vanes nullify the natural vortex action of the incoming water which might otherwise detract from the proper functioning of the pump. The absence of an inlet port adjacent to the high pressure cutoff point prevents a conflicting flow of water, thus also minimizing the noise when operating with only residual water in the pump cavity.

The operation of the outlet valve 50 is particularly effective in that the free action of the valve seat assembly operates as a check when the motor is stopped, to prevent the water in the drain tube 48 from flowing back into the pump cavity and the bottom of the tub. At the end of the drain cycle when the last of the water is being emptied from the tub, air begins to enter the pump. At this moment, the tube 48 is full of water by virtue of the pressure created by the revolving pump blades accelerating the water. Air, however, cannot be accelerated with equal facility by the pump blades and the pressure at the base of this vertical water column falls off. Without the free valve seating action of the valve 50, water would drain back into the pump chamber until enough water (and resultant pressure) accumulate to again force the water up the tube. A cyclic surging action would result, creating a noise that would be disturbing to the operator. However, the valve seat is free to close when the water flow ceases and by preventing air from entering, the water is held in tube 48 until enough pressure is created by the pump to lift the valve seat assembly. Thus, although the final drainage from the tub may be intermittent, the disconcerting "surging" noise is not present.

While I have shown a particular embodiment of my invention, it will be understood, of course, that I do not wish to be limited thereto since many modifications may be made; and I therefore contemplate by the appended claims to cover any such modifications as fall within the true spirit and scope of my invention.

What I claim as new and desire to secure by Letters Patent of the United States is:

1. In a dish washing machine, a tub having a depending bottom wall portion at its lower end which defines an impeller chamber, an impeller in said impeller chamber for circulating water from such chamber throughout the tub and from which it flows back to such chamber, a closure for the upper end of the tub having top and bottom walls which define a water chamber, a wall projecting upwardly from said bottom wall which defines an overflow passage through said bottom wall and serves to define a liquid level in said water chamber, an opening in said bottom wall through which liquid in said water chamber may flow directly to said impeller chamber whereby a volume of wash water measured in said water chamber may be supplied to said impeller chamber, a discharge conduit connected to the bottom of said impeller chamber, an inlet valve for closing said opening, means connected with said valve for opening and closing it, and a conduit connected to said water chamber through which water may be supplied to it.

2. In a dish washing machine, a tub having a

conical bottom wall portion at its lower end which defines an impeller chamber, an impeller in said impeller chamber for circulating water from such chamber throughout the tub and from which it flows back to such chamber, a closure for the upper end of the tub having top and bottom walls which define a water chamber, a wall projecting upwardly from said bottom wall which defines an overflow passage through said bottom wall and serves to define a liquid level in said water chamber, an opening in said bottom wall through which liquid in said water chamber may flow directly to said impeller chamber whereby a volume of wash water measured in said water chamber may be supplied to said impeller chamber, a discharge conduit connected to the bottom of said impeller chamber, an inlet valve for closing said opening, an outlet valve for the discharge conduit, means connected to said valves which when operated effects the opening of one of said valves and the closing of the other, and a conduit connected to said water chamber through which water may be supplied to it.

3. In a dishwashing machine, a tub having a depending bottom wall portion at its lower end which defines an impeller chamber, an impeller in said impeller chamber for circulating water from such chamber throughout the tub and from which it flows back to such chamber, a hinged closure for the upper end of the tub having top and bottom walls which define a water chamber, a wall projecting upwardly from said bottom wall which defines an overflow passage through said bottom wall and serves to define a liquid level in said water chamber, an opening in said bottom wall through which liquid in said water chamber may flow directly to said impeller chamber, whereby a volume of wash water measured in said water chamber may be supplied to said impeller chamber, a detergent receptacle connected to the under side of said bottom wall in line with said opening, a discharge conduit connected to the bottom of said impeller chamber, an inlet valve for closing said opening, means connected with said valve for opening and closing it, and a conduit connected to said water chamber through which water may be supplied to it.

4. In a dish washing machine, a tub having an impeller chamber at its lower end, an impeller in said impeller chamber for circulating water from such chamber throughout the tub and from which it flows back to such chamber, a closure for the upper end of the tub having top and bottom walls which define a water chamber, a wall projecting upwardly from said bottom wall which defines an overflow passage through said bottom wall and serves to define a liquid level in said water chamber, an opening in said bottom wall through which liquid in said water chamber may flow directly to said impeller chamber whereby a volume of wash water measured in said water chamber may be supplied to said impeller chamber, a drain pump having its inlet connected to the bottom of said impeller chamber, a discharge conduit which extends upwardly along the side of said tub with its lower end connected to the drain pump outlet, an inlet valve for closing said opening, an outlet valve for the upper end of the discharge conduit, means connected to said valves which when operated effects the opening of one of said valves and the closing of the other, and a conduit connected to said water chamber through which water may be supplied to it.

5. In a dish washing machine, a tub having an open top, a hinged cover for the open top com-

prising top and bottom walls which define a water chamber, means projecting upwardly from said bottom wall which defines an overflow opening whereby a measured volume of water may be supplied to said water chamber, a baffle plate carried by said bottom wall beneath said overflow opening for distributing water overflowing therethrough over dishes in said tub whereby they may be given an initial rinsing, a bottom wall for the tub shaped to define an impeller chamber, an impeller in the impeller chamber for circulating water over dishes in the tub, an opening in the bottom wall of the cover through which a volume of water measured in the water chamber may be supplied directly to the impeller chamber, a valve for closing said opening, means for operating said valve, a water supply conduit connected to said water chamber, and a discharge conduit connected to the bottom of said impeller chamber.

6. In a dish washing machine, a tub having an open top, a hinged cover for the open top comprising top and bottom walls which define a water chamber, a water supply conduit connected thereto, means projecting upwardly from said bottom wall which defines an overflow opening whereby a measured volume of water may be supplied to said water chamber, a bottom wall for the tub shaped to define an impeller chamber, an impeller in the impeller chamber for circulating water over dishes in the tub, a supply opening in the bottom wall of the cover through which a volume of water measured in the water chamber may be supplied directly to the impeller chamber, a drain pump having its inlet connected to the bottom of the impeller chamber, a discharge conduit for the pump, the discharge end of which terminates adjacent to said cover, an inlet valve for closing said supply opening, a discharge valve for closing the end of said discharge conduit, and an operating member carried by the cover for controlling said valves which when moved to one position effects the opening of one of said valves and the closing of the other and when moved to another position effects the opening of the other of said valves and the closing of the one valve.

7. In a dish washing machine, a tub having an open top, a hinged cover for the open top comprising top and bottom walls which define a water chamber, a water supply conduit connected thereto, means projecting upwardly from said bottom wall which defines an overflow opening whereby a measured volume of water may be supplied to said water chamber, a bottom wall for the tub shaped to define an impeller chamber, an impeller in the impeller chamber for circulating water over dishes in the tub, a supply opening in the bottom wall of the cover through which a volume of water measured in the water chamber may be supplied directly to the impeller chamber, a drain pump having its inlet connected to the bottom of the impeller chamber, a discharge conduit for the pump, the discharge end of which terminates adjacent to said cover, an inlet valve for closing said supply opening, a discharge valve for closing the end of said discharge conduit, a valve control member which in one position holds the discharge valve closed and in another position permits it to be opened by pressure in the discharge conduit, and an operating member carried by the cover for controlling said inlet valve and said valve control member which when moved to one position effects the opening of said inlet valve and move-

ment of said valve control member to close the discharge valve and when moved to another position effects the closing of the inlet valve and the movement of said valve control member away from said discharge valve whereby it may be opened by pressure in said discharge conduit.
